UNITED STATES PATENT OFFICE

LEMUEL F. HOWARD, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY CAR RETARDER

Application filed July 10, 1928. Serial No. 291,622.

My invention relates to railway car retarders of the type involving brake beams located in the trackway and movable into engagement with the wheels of a car for the purpose of retarding the motion of the car.

One feature of my invention is the provision of a car retarder of this type in which the brake beam is made up of a series of non-articulated sections.

10 I will describe one form of car retarder embodying my invention, and will then point out the novel features thereof in claims.

The accompanying drawing is a plan view showing one rail of a railway track having associated therewith one form of car retarder embodying my invention.

Referring to the drawing, the reference character 1 designates a track rail along which cars normally move in the direction indicated by the arrow. Located on one side of this rail is a brake beam made up of a series of sections 6^a, 6^b, 6^c, etc.; and located on the other side of the rail is another brake beam made up of a series of sections 7^a, 7^b, 7^c. Each brake beam section is provided with the usual wheel-engaging shoe 5. Associated with each section of each brake beam are a plurality of springs G, for biasing the section toward the wheels of a car on the track.

15 1. As here shown, one end of each spring is pivotally attached to the brake beam section, and the other end is pivotally fixed to a bar 70 by means of an abutment D. Each bar 70 is rigidly attached to the track ties, which

35 are not shown in the drawing. The axis of each spring G is disposed at an angle less than 90° to the track rail, so that longitudinal motion of the brake beam sections in lines parallel with the track rail will result in 40 movement of these sections toward and away from the rail, that is, into closed and open positions of the retarder. The brake beam sections may be moved longitudinally by any 45 suitable means, such, for example, as the mechanism shown and described in application for Letters Patent of the United States, filed by W. C. McWhirter, April 29, 1927, Serial No. 187,525, which became Patent No. 50 1,744,833. This operating mechanism is

omitted from the drawing because it forms no part of my invention.

The sections of each brake beam are non-articulated, that is, there is no mechanical connection between adjacent sections, and there is no provision for movement of one section due to movement of an adjoining section. Each section, however, is so disposed that its entering end is farther from the track rail than its leaving end, although the angle which each section makes with the track rail is exaggerated in the drawing to more clearly illustrate this feature of my invention. The parts are so adjusted that when the retarder is closed, and a car wheel passes through a given section, the car wheel will compress the spring G at the entering end of the section by only a relatively small amount, but will compress the spring at the leaving end of the section by a considerably greater amount, 60 the amount of compression of the successive springs progressively increasing as the car passes through the section. Furthermore, the springs are so designed or adjusted that substantially the same pressure is exerted against 65 the car wheel at all points in the section, and for this purpose the pressure per unit of compression of the spring by the car wheels at the entering end of each section is relatively high, 70 whereas the pressure per unit of compression for succeeding springs progressively decreases to a minimum for the spring at the 75 leaving end of the section.

It will be seen from the foregoing, that 80 when the retarder is closed, the entering end of each brake beam section is at substantially the same distance from the rails when the section is unoccupied as when a car occupies the entering end of the section. As a car wheel passes through a given section, and approaches the leaving end of the section, the leaving end is pushed back by the wheels, so that as the wheel leaves the section the leaving end is practically in alignment with the 85 entering end of the next succeeding section. This makes it unnecessary to articulate the sections or to provide means for moving the entering end of the section away from the track rail while a car occupies the leaving end 90 of the next section in the rear.

Although I have herein shown and described only one form of retarder embodying my invention, it is understood that various changes and modifications may be made therein within the scope of the appended claims without departing from the spirit and scope of my invention.

Having thus described my invention, what I claim is:

1. A railway car retarder comprising a series of non-articulated brake beam sections located beside a track rail and movable towards and away from the rail to closed and open positions, and springs for each section for biasing the section towards the rails, the parts being so designed that when the retarder is closed the entering end of each section is farther from the rail than the leaving end, and said springs being so proportioned and adjusted that when the retarder is closed and a car passes through the retarder the relatively small compression of the spring at the entering end of each section causes substantially the same pressure against the wheel as the relatively large compression of the spring at the leaving end.
2. A railway car retarder comprising a series of non-articulated brake beam sections located beside a track rail and movable towards and away from the rail to closed and open positions, and springs for each section for biasing the section towards the rails, the parts being so designed that when the retarder is closed the entering end of each section is farther from the rail than the leaving end, and the characteristics of the springs associated with each section being progressively varied so that when the retarder is closed the pressure exerted on a car wheel by each section is substantially the same at all points in the section.
3. A railway car retarder comprising a series of non-articulated brake beam sections located beside a track rail and movable towards and away from the rail to closed and open positions, and springs for each section for biasing the section towards the rails, the parts being so designed that when the retarder is closed the entering end of each section is farther from the rail than the leaving end, and the pressure per unit of compression of the springs being progressively decreased from the entering to the leaving end of each section, so that when the retarder is closed the pressure exerted on a car wheel is substantially the same at all points in each section.
4. A railway car retarder comprising two series of oppositely disposed non-articulated brake beam sections located one on each side of a track rail and each section movable toward and away from the rail to closed and open positions, and springs for each section for urging the section towards the rail, the parts being so designed that when the re-

tarder is closed the opening between opposite sections is greater at the entering end than at the leaving end, and the characteristics of the springs associated with each pair of oppositely disposed sections being such that the pressure exerted on a car wheel is substantially the same at all points.

In testimony whereof I affix my signature.

LEMU^E F. HOWARD.
